CLAMP

Clarence L. McCullough, Zanesville, Ohio

Application July 27, 1943, Serial No. 496,345

1 Claim. (Cl. 144—290)

My invention relates to improvements in clamps for holding pieces of work, such as small machine parts, to a fixed part of a machine or other object.

The primary object of my invention is to provide a simply constructed, easily operated clamp equipped to yieldingly oppose variable pressure against the piece of work, and which is adapted for quick release, easy adjustment in a fine degree for use with pieces of work of different thicknesses, is inexpensive to manufacture and will not readily get out of order.

Other and subordinate objects are also comprehended by my invention, all of which, together with the precise nature of my improvements, will be readily understood when the succeeding description and claims are read with reference to the drawing accompanying and forming part of this specification.

In said drawing:

Figure 1 is a view in plan illustrating my improved clamp in its preferred embodiment.

Figure 2 is a view in side elevation,

Figure 3 is a detail view in horizontal section taken on the line 3—3 of Figure 2, and

Figure 4 is a view partly in side elevation and partly in section of the clamping leg and foot.

Referring to the drawing by numerals, my improved clamp, as illustrated, comprises a bracket 1 including a base plate 2 adapted to be attached to a fixed part 3 by means of machine screws 4, and a pair of opposed, laterally spaced, parallel webs 5 extending from said base plate 2 at right angles thereto.

A bifurcated clamping arm 6 is pivoted at one end, as at 7, to said webs 5 adjacent one end of the bracket to be swung between the webs in opposite directions toward and from said plate 2, respectively. The clamping arm 6 is constructed and arranged to provide an enlarged, semi-cylindrical, socket-forming free end 8 thereon as best shown in Figure 3.

A clamping leg extends from said free end 8 of the clamping arm 6 at a right angle to said arm and comprises a threaded bolt 9 slidably extended through the socket formed by said end 8 of the arm 6 for longitudinal adjustment in said arm 6. A pair of lock nuts 10 on the bolt 9, at opposite sides of said arm 6, provides for adjusting the bolt, and leg, into different set positions. A hollow, resilient foot 11 surrounds the head 12 of the bolt 9 for clamping engagement with a piece of work represented at 13. Preferably the foot 12 is provided with a serrated base 14 for engagement with the piece of work 13.

A rivet 15 extends transversely through the webs 5 adjacent the end of the bracket 1 opposite to that near which the pivot 7 is located. The purpose of the rivet 15 will presently appear.

A clamping lever 16 is pivoted at one end, as at 17, to the clamping arm 6, intermediate the ends of the latter, for swinging between the furcations of said clamping arm 6 in opposite directions. The clamping lever 16 is provided at its pivoted end with an edge hook 18 adapted to be swung into and out of the space between the webs 5 and into and out of straddling relation to the rivet 15 under swinging of the clamping lever 16 in opposite directions, respectively. The hook 18 is provided with an inner edge 19 eccentric to the pivot 17 of the clamping lever 16 and for camming engagement with the rivet 15, the arrangement being such that if the clamping arm 6 is swung toward the support 3 to engage the clamping foot 11 with the piece of work 13, and the clamping lever 16 is then swung in a proper direction to swing the hook 18 into clamping engagement with the rivet 15, said eccentric edge 19 of the hook 18 will coat with the rivet 15 to cam the clamping arm 6 in the direction of the piece of work and thereby tighten the clamping foot 11 against said work. A suitable thumb piece 20 is provided on the end of the clamping lever 16 opposite to the end equipped with the hook 18.

The manner in which my improved clamp is designed to be operated to exert pressure against the piece of work 13 and thereby clamp the same in position against the part 3 having been set forth in the foregoing, need not be further explained.

To release the piece of work 13, it is merely necessary to swing the clamping lever 16 in the proper direction to withdraw the hook 18 from straddling relation to the rivet 15, as will be clear. In this connection, it is to be noted that the hook 18 need not be completely withdrawn from between the webs 5 to release the clamp and that the clamping pressure exerted by the foot 11 may be varied by virtue of the gradual camming action which may be effected by the edge 19 and rivet 15 in different positions of the clamp lever 16. By adjusting the leg 9 in the clamping arm 6, in the manner already described, the clamp may be conditioned to effect the desired clamping action against work pieces 13 of different thicknesses.

The foregoing will, it is believed, suffice to impart a clear understanding of my invention.

Manifestly, the invention, as described, is susceptible of modification without departing from the inventive concept, and right is herein re-

served to such modifications as fall within the scope of the appended claim.

What I claim is:

A clamp for use on a fixed part of a machine or the like to clamp a piece of work against said part comprising a bracket adapted for attachment to said part, a clamping arm pivotally mounted at one end on said bracket for swinging toward and from said part, a clamping leg extending from the other end of said arm at a 10

right angle thereto for engagement with the piece of work, a member mounted on said bracket, and a clamping lever pivoted at one end to said arm intermediate the ends of the latter for swinging on said arm, said lever including a hook on the pivoted end thereof for camming engagement with said member when swinging the lever toward said part to force the arm toward, and the clamping leg against the piece of work.

CLARENCE L. McCULLOUGH.
